UNITED STATES PATENT OFFICE.

JOHN H. BLANCHARD, OF BOSTON, ASSIGNOR OF ONE-FOURTH TO HENRY E. WAITE, OF NEWTON, MASSACHUSETTS.

CAR-COUPING.

SPECIFICATION forming part of Letters Patent No. 245,770, dated August 16, 1881.

Application filed June 16, 1881. (No model.)

To all whom it may concern:

Be it known that I, JOHN H. BLANCHARD, a citizen of the United States of America, residing at Boston, in the county of Suffolk and 5 State of Massachusetts, have invented certain new and useful Improvements in Car-Couplings; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 This invention relates to car-couplings; and it consists in the construction and arrangement of parts as hereinafter more fully described and claimed.

In the annexed drawings, which fully illustrate the invention, Figure 1 is a plan view. Figs. 2 and 3 are longitudinal sections. Fig. 4 is an end view of car, showing a transverse section through the draw-head, taken on the line *xx* of Fig. 1. Fig. 5 is a view of the under side of draw-head and draw-bar. Fig. 6 is a perspective view of draw-bar. Fig. 7 represents a side view and plan of coupling hook or link.

Like letters of reference indicate corresponding parts in the several views.

The draw-head A, which is constructed of cast-iron or other suitable material, is provided on its under surface with a central longitudinal slot or groove, *a*, for the reception of the 35 wrought-iron draw-bar B, a recess or depression, *a'*, having beveled sides, being formed at the inner end of the slot *a*, into which fits a correspondingly-formed shoulder, *b*, on the end of the detachable draw-bar. This enlarged 40 head or shoulder fitting within the recess *a'* serves to assist the pins *b' b'* in holding the draw-bar in place. By this construction the objectionable effects of casting the draw-head around the wrought-iron tongue or bar, which 45 tends to chill the latter and renders it more liable to break, are obviated, and the parts may also be more easily repaired or replaced when necessary.

In the upper part of each draw-head on one 50 side is a recess, *C*, open at the top, in which is

pivoted a coupling hook or link, *D*. The hooked end of this link is beveled upward and outward to correspond with the face of a catch, *E*, on the opposite draw-head, which catch is beveled or inclined upward and inward, so that the end 55 of the link *D* will pass readily over it and bring its eye or slot *d* into engagement with the catch *E* in coupling two adjoining cars. At the lower portion of the beveled end of the link *D* is a projection, *d'*, which fits into a depression at 60 the back of the catch *E* and renders the coupling more secure. The beveled catch *E* on each draw-head is located at the front end or mouth of a recess, *C'*, which adjoins the recess *C*, and, like the latter, is open at the top. This recess 65 *C'* is beveled or inclined backward, from below upward, at its rear end, to accommodate the movements of the hooked link *D*. The inclined rear portion of the recess *C'* is slotted for the reception of a lever, *F*, which is pivoted in lugs 70 or bearings *c'* at the top of the incline, and lies under the beveled end of the hook or link *D* when the cars are coupled.

At the upper or rear end of the recess *C* in each draw-head are lugs or bearings *c*, in which is pivoted a lever, *G*, the shorter end of which bears upon the top of the link *D* at its rear end, while the longer or rear end of the lever *G* is connected by a chain, *g*, with a lever-handle, *H*, attached to the end of the car *I*. The lever-handle *H* is also connected by a chain, *f*, with the lever *F*, and by a chain or cord, *i*, with the top of the car. 80

It will be seen that by operating the lever-handle *H* either directly from the side of the car or through the chain *i* from the top of the car the chains *f g* will actuate the levers *F G* to simultaneously raise both links, one being raised by the lever *F* pushing the beveled end of the link upward and the other by the lever *G* bearing down upon the rear end of the link. 90

The recesses *C C'*, in which the links are engaged, are beveled or flared outward at the sides, so as to afford the links sufficient lateral play. These links are preferably constructed 95 of wrought-iron, and are pivoted in their respective recesses by pins *e e*, so as to be capable of being readily removed when desired.

A stop-pin, *e'*, may be placed in each recess *C*, if desired, to limit the movement of the link. 100

In order to facilitate coupling with cars provided with the ordinary links, each draw-head is provided with a cavity, *h*, for the reception of said links, suitable openings, *h'*, being provided in each for the passage of the ordinary coupling-pin.

Having thus described my invention, what I claim as new, and desire to secure by Letters Patent, is—

1. The combination, with the draw-head *A*, having slot or groove *a* and recess *a'* on its lower surface, of the detachable draw-bar *B*, having enlarged head or shoulder *b*, and secured by pins *b' b'*, substantially as and for the purpose specified.

2. The combination, with the draw-heads *A*, having recesses *C C'*, lugs *c c'*, and beveled catch *E*, of the coupling hooks or links *D*, having slots *d*, and beveled ends provided with projections *d'*, and adapted to be operated by the levers *F G*, substantially as and for the purpose set forth.

3. The combination of the draw-heads *A*, having open-top recesses *C C'*, beveled catch *E*, and lugs *c c'*, the levers *F G*, pivoted in said lugs, the slotted coupling-hooks *D*, pivoted in the recesses *C*, with a lever, *F*, resting below the beveled end of each, and lever *G*, bearing down upon the rear end, and the lever-handle *H*, provided with chains or cords *f g i*, connecting said handle with the levers *F G* and with the top of the car, whereby both coupling-hooks may be simultaneously operated from the top or side of either car, substantially as shown and described.

In testimony whereof I affix my signature in presence of two witnesses.

JOHN H. BLANCHARD.
